Application July 14, 1950, Serial No. 173,824

6 Claims. (Cl. 250—85)

1

This invention relates to lamps of the type sold to the general public for household use as sun lamps and including a source of ultraviolet radiation and preferably also a source of infrared radiation.

The usual method of providing ultraviolet radiation in sun lamps is to operate a mercury vapor arc in series with a suitable ballast resistance, which may be designed to provide infrared radiation if desired. Such lamps are illustrated for example by the prior U. S. Patent No. 2,369,987 and also by the copending application of George F. Embshoff, Serial No. 52,363, filed October 1, 1948. The desirable and beneficial ultraviolet wave lengths are those longer than about 2800 Angstroms, whereas shorter wave lengths may have harmful effects. Since the spectrum of the mercury arc emits substantial amounts of energy at these undesirable shorter wave lengths, the usual practice in sun lamps is to enclose the arc in glass which filters out most if not all of the radiation below about 2800 Angstroms. On the other hand, as the operating temperature and vapor pressure in the arc increase, the ultraviolet energy output in the region of the desirable longer wave lengths mentioned above also increases. Hence for sun lamp purposes, it is desirable to utilize the heat developed by the ballast resistance not only to provide infrared radiation but also to increase the operating temperature of the arc and with it the vapor pressure as rapidly as possible. These effects are facilitated when one or more elongated ballast resistors are arranged parallel with and closely adjacent to a tubular arc burner, whereby heat losses are minimized and the ballast heat is distributed more or less uniformly throughout the length of the arc as disclosed in the aforesaid Embshoff application.

The present invention relates to a lamp of the type characterized above, and one of its objects is to provide an improved lamp of this type in the form of a portable unit for household use which is simple and inexpensive in construction, which is convenient to handle and use, and which produces an effective output of both ultraviolet radiation and infrared radiation or optionally of infrared radiation only.

Another object is to provide a lamp of the type characterized above having improved means for housing the ballast resistor elements and for utilizing the heat developed thereby to improve the operation of the arc burner.

Another object is to provide a lamp of the type characterized above embodying a novel combination and arrangement of ultraviolet generator, infrared generator and reflector whereby both types of radiation are effectively combined and radiated from the lamp.

A further object is to provide an improved re-

10 reflector for use in a lamp of the above type which provides substantially uniform energy distribution over the intended target area.

15 A further object is to provide a lamp of the type characterized above having improved means for mounting the burner tube and the resistor element or elements in association with the reflector which suitably directs the emitted radiation.

20 A still further object is to provide an improved housing for a lamp of the type characterized above having a base and a relatively movable cover unit comprising a reflector, an ultraviolet lamp or burner, and suitable ballast resistors, said cover unit being movable relatively to the base to an open position for operation of the lamp and to a closed position in which the operating parts are substantially completely enclosed.

25 In a lamp of the type described above, the glass walls of the burner tube are exposed to considerable heat and care must be taken that they do not reach a temperature at which the glass softens and the tube is damaged or destroyed. The danger of overheating is increased as the mercury vapor pressure increases and the arc changes from a diffused glow to a concentrated stream, because of the frequent tendency of such concentrated arc streams to follow a bowed or curved path between the electrodes and thus to approach closely to or even to touch the glass wall of the tube. Another object of the invention is to overcome this tendency and to confine the concentrated arc stream more or less closely to a straight axial path.

30 Other objects will appear hereinafter as the description of the invention proceeds.

35 Two embodiments of the invention have been illustrated in the accompanying drawings, but it is to be expressly understood that such drawings are for purposes of illustration only and are not to be taken as a definition of the limits of the invention, reference being had to the appended claims for this purpose.

In the drawings,

40 Fig. 1 is a side view of a lamp embodying the invention in its operating position;

Fig. 2 is a front view of the lamp shown in Fig. 1;

Fig. 3 is a section on the line 3—3 of Fig. 2;

45 Figs. 4 and 5 are sections on the lines 4—4 and 5—5 of Fig. 3;

Fig. 6 is a section on the line 6—6 of Fig. 3;

50 Figs. 7, 8, 9, 10 and 11 are sections on the lines 7—7, 8—8, 9—9, 10—10, and 11—11 respectively of Fig. 3;

55 Fig. 12 is a perspective view illustrating the physical arrangement and connections of the electrical elements;

Fig. 13 is a wiring diagram;

Fig. 14 shows a different arc tube construction embodying the invention;

Fig. 15 is a section on the line 15—15 of Fig. 14;

Fig. 16 is a diagram explanatory of the design 5 of the reflector;

Fig. 17 is a transverse section through the reflector;

Fig. 18 shows somewhat diagrammatically the appearance of the reflecting surface; and 10

Fig. 19 illustrates the operation of the reflector.

A lamp embodying the invention comprises a housing formed in two parts capable of substantially completely enclosing all of the operating elements of the lamp when not in use as described 15 hereinafter. One of the housing parts forms a base which may be made of any suitable material such as metal, molded plastic, rubber or the like, and which may have any suitable shape, this base preferably being recessed or dished to form a 20 larger housing cavity. The other housing part comprises a cover unit pivoted to the base at one end on a horizontal axis to swing from a more or less upright open operating position downwardly into juxtaposition with the base to close the 25 housing. This cover unit includes all of the essential operating parts of the lamp, comprising a substantially tubular ultraviolet arc burner and a suitable resistance means which serve as ballast for the arc and also for emission of infrared 30 radiation, the lamp and the resistance means being assembled rigidly with a suitable reflector and these parts being partially enclosed by an outer cover element that is shaped to cooperate with the base and that may be made of any suitable material similar to or the same as that of the base.

In the form shown, the base comprises a pressed or stamped sheet metal pan of more or less oblong shape with rounded ends or corners, the base having a peripheral wall 1 adapted to rest on a supporting surface, a substantially flat horizontal margin 2, and a recess or cavity 3. The cover unit is secured to this base at one end by any suitable type of pivot mounting. For example, a 40 bracket 4 is secured to one end of the base 1, said bracket having upwardly extending ears or lugs 5 which fit between corresponding ears or lugs 6 of a second bracket 7, the two brackets being pivotally connected by means of a pivot pin 8 passing through the lugs and held in place by rivets 9. The cover unit, which is indicated generally at 10 in Figs. 1 and 3, is connected to and carried by the bracket 7 of the pivot mounting in any suitable manner as described in detail hereinafter.

The ultraviolet lamp or burner forms part of the cover unit 10 and is preferably of the same general type as those disclosed in the prior patent and application mentioned above, its details being illustrated in Figs. 3 and 6-10. As shown in these figures, the glass wall 11 of the burner is substantially tubular in shape and is suitably closed and sealed at each end as by means of stems and presses 12 of the usual type. This bulb contains a quantity of vaporizable and ionizable material such as mercury, and is usually filled with argon or other suitable rare gas at a low pressure. Preferably the quantity of mercury employed is limited so as to prevent the development of unduly high mercury vapor pressures when the lamp is in operation. Mounted in the press 12 at one end of the lamp is a wire or conductor 13 leading to an arc electrode 14. A similar wire or conductor 15 is mounted in the 70

press 12 at the opposite end of the lamp and leads to an arc electrode 16. Filaments 17 and 18, which are preferably coated with or otherwise embody a suitable electron-emissive substance, are connected at one end to the leads 13 and 15 respectively and at the other end to wires or conductors 19 and 20 respectively which lead out through the presses 12.

When an arc is formed between the electrodes 14 and 16 as hereinafter described, and as the mercury vapor pressure increases and the arc becomes concentrated, the path of the arc often tends to bow or curve instead of following a straight axial path between the electrodes and thus to approach closely to the glass wall 11. In order to avoid possible softening of the glass due to such bowing, arc centering means are preferably provided between the two electrodes 14 and 16. These means comprise one or more arc centering devices 21 each provided with a central aperture through which the arc stream passes, and are electrically disconnected from the electrodes and filaments mentioned above, being supported in the bulb in any suitable manner as by attachment to the tubular wall 11 or to the presses 12. The arc centering devices may comprise discs of metal or of refractory nonconductive material such as ceramic or, as in the form shown, loosely wound spirals of refractory metal wire such as molybdenum and the like.

The ballast resistance for the arc preferably takes the form of an elongated unit arranged parallel with and closely adjacent to the tubular ultraviolet burner 11 so that the heat developed in the ballast is distributed uniformly throughout the length of the lamp as explained above. Also this unit is preferably mounted between the burner tube and an associated reflector all of which elements form part of the cover unit 10, this arrangement avoiding interference with direct radiation of ultraviolet light and at the same time resulting in the reflection of both ultraviolet radiation and infrared radiation and the distribution of the radiation from both sources over substantially the same area as described hereinafter. The electrical characteristics usually make it desirable to employ two ballast resistors for this purpose, each having a length equivalent to that of the arc tube, these resistors and the arc path between the electrodes 14 and 16 being connected in the operating circuit of the lamp so that the resistors are in series with each other and with the arc path. A starting circuit may also be connected across the filaments 17 and 18 externally of the lamp bulb to assist in starting the arc as described below. In case it may be desired to operate the lamp as an infrared generator only, a third resistor and switch are connected in a circuit in shunt to the electrodes 14 and 16. These resistors are combined in the single elongated unit mentioned above.

The connections between the elements mentioned above and the operating circuits will be better understood from Figs. 12 and 13. The lamp is energized by insulated supply lines 22 and 23, preferably in the form of the usual supply cord 24. Inside the lamp, the supply lines are separated and the line 22 leads to a binding post 25 from which a connecting wire 26 leads to one end of a ballast resistor 27 which is parallel to and of approximately the same length as the lamp bulb 11. The other end of the resistor 27 is connected by a wire 28 with the adjacent end of a second resistor 29, also 75 parallel to and of substantially the same length

as the lamp bulb 11, and the other end of the resistor 29 is connected by a conductor 30 with a binding post 31. A conductor 32 connects the binding post 31 with the lead-in wire 13 and the electrode 14. At the opposite end of the lamp, the electrode 16 and its lead-in wire 15 are connected at 33 with a wire 34 passing through one side of a double insulating tube 35 of ceramic or like material and thence to a binding post 36 at the other end of the lamp, the line conductor 23 being connected to this binding post. Reference to Fig. 13 shows that in the normal operation of the lamp, the current flows through a series operating circuit comprising conductors 22 and 26, resistor 27, wire 28, resistor 29, wires 30, 32 and 13, electrodes 14 and 16, wires 15 and 34, and line conductor 23.

The arc may be started either automatically or manually. In the form shown, the starting circuit includes the filament lead-in conductor 19 which is connected to a suitably insulated wire 37 leading to one terminal 38 of a manual starting switch indicated generally at 39, the other terminal 40 of this switch being connected to a suitably insulated wire 41 from which a wire 42 leads to the opposite end of the lamp where it passes through an insulating tube 43 of ceramic or like material and is then connected at 44 with the filament lead-in conductor 20. The starting switch 39 is of any suitable type which normally remains open but can be held closed long enough to start the operation of the lamp. Referring to Fig. 13, the starting current passes from line conductor 22 through wire 26 and resistor 27, wire 28 and resistor 29, wires 30, 32 and 13, filament 17, wires 19 and 37, switch 39, wires 42 and 20, filament 18, wires 15 and 34 and supply line 23. As the filaments become hot, electronic emission therefrom will result in ionization of the atmosphere in the arc bulb. After a brief initial period, the starting switch 39 is released and opens to break the starting circuit described above and the main arc then strikes between the electrodes 14, 16 through the ionized atmosphere, the current then flowing through the series operating circuit mentioned above.

In order to operate the lamp as an infrared generator only, a suitably insulated conductor 45 leads from the binding post 31 mentioned above to one terminal 46 of a switch indicated generally at 47, the other terminal 48 of the switch being connected by a conductor 49 with a binding post 50 from which a conductor 51 leads to one end of a third resistor 52 that is parallel to and has substantially the same length as the arc bulb 11. From the other end of this resistor, a wire 53 leads to the junction 33 mentioned above, preferably passing through the other side of the insulation tube 35. When the switch 47 is closed, therefore, the resistor 52 shunts the arc path between the electrodes 14 and 16, the current then flowing through a series circuit comprising the line conductor 22, wire 26 and resistor 27, wire 28 and resistor 29, wire 45, switch 47, wires 49 and 51, resistor 52, wires 53 and 34, and line conductor 23. Hence the arc does not operate, but the three resistors 27, 29 and 52 are connected in series across the lines 22, 23 to provide infrared radiation.

The three elongated resistors mentioned above are combined in a single unit by enclosing them in ceramic material capable of being heated by the resistors to a temperature at which infrared radiation is emitted. Also the connecting wires which extend between the opposite ends of the lamp should be insulated, these including

the wire 42 in the starting circuit and the wire 34 in the operating circuit. For these purposes the present invention makes use of a single rod or tube 54 of suitable ceramic material having a plurality of longitudinal bores or holes of the appropriate size to receive the electrical elements to be insulated. This ceramic rod may have any desired cross-sectional shape, being shown as substantially triangular, and is of substantially the same length as and substantially parallel with the lamp bulb 11. Three large bores or holes of diameter sufficient to receive the resistor coils 27, 29 and 52 extend longitudinally throughout the entire length of the ceramic rod 54 as shown in Figs. 7 and 8, these large holes being preferably arranged adjacent the corners of the triangularly shaped rod. The wires 34 and 42 pass through smaller holes arranged between the larger bores mentioned above.

The ultraviolet tube 11 and the ceramic tube 54 are rigidly assembled together in parallel, closely spaced relation by suitable means, preferably clamps which also serve to transmit heat to the tube 11. In the form shown, each pair of adjacent ends of the tube and rod are gripped by a pair of appropriately shaped clamping elements 55, the clamps being suitably tightened as by means of a pair of bolts 56 and nuts 57, these bolts passing through the clamps between the tube and rod. These clamps conduct heat directly from the ceramic tube 54 to the ends of the burner tube 11 which, if heated only by radiation, would be so cool that part of the mercury would condense therein and the desired high pressure arc would not be obtained. As the clamps 55 do not completely surround the tube 11, but leave a portion thereof exposed, rings 58 may also be slipped onto both ends of the tube outside the clamps.

As stated above, the combined ultraviolet tube and ceramic rod are associated with a cover element and reflector to form a cover unit that is pivoted to the base by means of the pivot bracket 7. The cover element may have any suitable exterior shape, and interiorly is recessed or dished to provide a cavity and a reflector therein which reflects the ultraviolet radiation and/or infrared radiation outwardly from the lamp when the cover unit is in operating position as shown in Fig. 1. Preferably the cover unit includes an angular supporting plate part of which forms a partition across the end of the cover element, said plate cooperating with the cover element to provide a compartment adjacent the pivot mounting for the switches 39 and 47, the supply cord 24, and the connections from these elements to the lamp and resistors. The assembled tube and rod are secured at one end of the assembly to the aforesaid partition and are thus mounted in the cavity of the cover unit in association with the reflector.

In the preferred construction shown in the drawings, the supporting plate mentioned above is made of stiff metal for greater strength and is utilized as the main load carrying element of the cover unit. It comprises a flat section 59 closing the end of the dished cover element 60, and a second flat section 61 arranged at right angles to the section 59 and forming a partition across the end of the cover element 60, the plate section and the cover element thus co-operating to provide a substantially closed compartment 62. The plate section 59 is suitably attached to the pivot bracket 7 as by means of an auxiliary bracket 63 riveted or bolted at 64 to the bracket 7 and having a flange 65 that is secured in any suitable manner

to the plate section 59, as for example by means of welding. The compartment 62 may be suitably ventilated, as by means of openings 66 in the plate section 61 and similar openings 67 in the cover element 60. The cover element 60 is secured in the desired position by means of a flange or extension 68 of the bracket 63 which is shaped to fit closely against the cover element and is secured thereto by means of a screw 69. The cover element may be additionally secured in position by means of screws 10 which engage tabs 71 formed on the upper edge of the plate section 61.

In order to support the assembled ultraviolet tube 11 and ceramic rod 54, and at the same time to insulate these elements and the various electrical connections described above from the metal supporting plate, the partition 61 is formed with a large central opening 72 (Fig. 5) and a base plate 73 and a terminal plate 74, both of suitable insulating material such as ceramic, are located on opposite sides of and assembled rigidly with the partition. The base plate 73 is held in spaced parallel relation with the partition 61 by means of tabs 75 turned at right angles to the plane of the partition at the edges of the opening 72 and engaging the base plate 73. The terminal plate 74 is held in spaced relation with the partition 61 and base plate 73 by means of a spacer boss 76 which extends through the opening 72 in the partition and into engagement with the base plate 73, and by means of small lugs 77 at the corners of the terminal plate which engage the partition. The assembled tube and rod and the plates 73 and 74 are secured rigidly with the partition 61 by means of a bolt 78 passing through an opening in the base plate 73 and through the boss 76, one end of the bolt being provided with an eye 79 through which one of the clamping bolts 56 passes and the other end of the bolt carrying a nut 80 that is screwed tight against the terminal plate 74. If desired, the surface of the base plate 73 may be recessed somewhat (Fig. 6) to receive the ends of the tube 11 and ceramic rod 54. The use of ceramic material for the plates 73 and 74 and the spacing of these plates also serve to minimize the amount of heat reaching the switches described below by radiation.

The opposite ends of the lamp tube 11 and ceramic rod 54 are unsupported, but are preferably connected together by a suitable cap 81 which houses the electrical connections and also serves to conduct heat from the ceramic element to the ultraviolet lamp so as to improve its operation and at the same time to minimize heat losses to the atmosphere.

The supply cord 24 mentioned above is brought into the compartment 62 through a suitable opening in the supporting plate section 59 in which the cord is preferably secured in any suitable manner as by means of a ferrule 82 of suitable insulating material and a strain clamp 83 (Fig. 11). The switches 39 and 47 are also mounted on the plate section 59 within the compartment 62, each switch casing being supported by a threaded stud 84 which passes through an opening in the plate 59 and is secured in position by means of lock nuts 85. The operating members 86 and 87 of the switches 39 and 47 respectively are located outside the compartment, and the plate 59 is preferably provided with circular louvers 88 to minimize the amount of heat reaching the switches by conduction. The binding posts 25, 31, 36 and 50 mentioned above are located on the terminal plate 74, and the various electrical connections to the lamp and to the

ceramic rod 54 extend through holes in the terminal plate, through the opening 72 in the partition 61, and through holes in the base plate 73 which are aligned with the various elements to which said conductors lead.

Preferably the ultraviolet burner 11 is guarded by a suitable screen or guard which, in the form shown, comprises transverse wires 89 and 90 having their ends inserted through openings in the opposite edges of the cover element 60 as shown in Fig. 4, and a longitudinal wire 91 (Figs. 1 and 2) having its ends curved inwardly toward and around the ends of the lamp, these wires being suitably interconnected as by spot welding to form an integral protective guard. Preferably this guard is also employed as a means for coiling the supply cord 24 when the lamp is not in use. To this end the wires 89 and 90 are turned substantially at right angles at the center line of the lamp as shown at 92 in Fig. 4 and are then turned again at right angles so that the central bight of each wire extends parallel with the axis of the burner tube toward the adjacent end of the tube as shown at 93 in Figs. 1 and 2. The wires 93 and 91 provide notches in which the supply cord 24 can be coiled as shown in Fig. 3 when the lamp is not in use. When the lamp is in operation, the cover unit is prevented from swinging to closed position by means of a coil spring 94 having one end secured to the supporting plate at 95 and its other end 96 projecting between the adjacent pair of wires 93 and terminating in a hooked end 97 (see Fig. 1). Coiling of the cord 24 in its notches depresses the spring element to the position shown in Fig. 3, where it is out of the way when the cover is closed.

It will be seen that when the supply cord is coiled in the position shown in Fig. 3, the cover unit comprising all of the operating elements of the lamp can be swung downwardly about the pivot axis 8 into juxtaposition with the base to provide a closed housing for all of these elements. For operation of the lamp, it is only necessary to swing the cover unit up about its pivot to the desired operating position and to uncoil the supply cord and plug it into a suitable source of current, this adjustment of the cover unit being facilitated by the provision of a suitable handle here shown as a knob 98. For ultraviolet radiation, the starting switch member 86 is held closed temporarily, closing the switch 39 and completing the starting circuit as explained above for a brief initial period, after which the member 86 is released and the switch 39 opens to start the arc between the electrodes 14 and 16, the current then flowing through the series operating circuit described above. In case it is desired to operate the lamp as an infrared generator only, the switch member 87 is operated to close the switch 47, thereby completing a series circuit through the resistors 27, 29 and 52 as described above. In this case the starting switch need not be operated and the arc does not start, since the filaments are not heated and since the voltage across the arc electrodes is only that across the resistor 52.

Figs. 14 and 15 show a modified form of arc burner that can be used in place of the one described above. The tubular glass bulb 100 corresponds to the bulb 11 described above, being mounted at each end by means of clamping members 101 and sleeves 102 similar to the parts 55 and 58 described above. Heat insulating material such as sheet asbestos 103 surrounds the clamping members 101, being interposed between

them and the sleeves 102 so as to minimize heat losses and to assist in keeping the ends of the tube hot and all the mercury vaporized. A cap 104 covers the end of the tube remote from the supporting ceramic plate 73.

The tube 100 is provided with arc electrodes 105, 106 and starting filaments 107, 108 preferably similar to the electrodes and filaments 14, 16, 17 and 18 described above and connected in circuits corresponding to Fig. 13.

Figs. 14 and 15 also show a modified form of arc centering means in the form of an arc reflecting grid located midway of the length of the tube at its hot side (i. e., the side next the ballast resistance unit). This grid comprises a length of molybdenum wire bent into generally triangular shape in a place perpendicular to the tube axis as shown at 109. Only one of these grids is required, although a plurality of grids can be employed if desired. The location of the grid prevents the arc from melting the glass wall of the tube at high output.

The grid 109 can be mounted in any suitable manner. In the form shown, the shank 110 of the molybdenum wire extends parallel to the axis of the tube and close to one side thereof and is welded at its end to a wire 111 which is mounted in the press 112 at the end of the lamp. Preferably both wires 110 and 111 are enclosed in insulating tubes 113 and 114 respectively which may suitably be made of glass. Without such protection, the arc may sometimes strike to and run down the wires 110 and 111 and melt the grid support, even though the wires are not electrically connected in the lamp circuit, particularly because the activating material from the starting filament 108 may sputter onto the grid support wires.

Sun lamps of the type herein described are used most frequently for the irradiation of relatively small areas of the body for short periods of time, and the lamp is located rather close to the target area, for example, at a distance of 18-24 inches. Hence in order to obtain the maximum benefit from the irradiation treatment and in the interest of efficient utilization of the energy of the lamp, it is very desirable to concentrate as much energy as possible within the target area and also to obtain substantially uniform energy distribution throughout the target area. These objectives present a difficult problem in a lamp of the type described above. Only a small part of the total energy of the ultraviolet burner is emitted directly to the target area, and only a still smaller part of the infrared energy because part of the target area is masked by the ultraviolet burner.

In order to utilize a greater proportion of the available energy, therefore, reflection of both infrared and ultraviolet energy to the target area is necessary. However, reflection of both types of energy from the same reflecting surface inside the cover 60 to the target area involves the difficulty that the two sources of energy are separate and spaced from one another so that a reflecting surface designed for one source will not be correct for the other. This condition is illustrated by Fig. 16 in which the curve 115 is a parabola having its focus at the point 116 representing the infrared generator, and the curve 117 is a parabola having its focus at the point 118 representing the ultraviolet generator. Referring to the upper half of Fig. 16, it is evident that a reflector corresponding to curve 115 would produce a parallel beam of reflected infrared

rays as indicated by the arrow 119 in broken lines, but that a large part of the ultraviolet energy would be reflected at such an angle as to miss the target area as indicated by the arrow 120 in solid lines.

Now referring to the lower half of Fig. 16, it will also be seen that if small portions 121 of the reflecting surface, located in its outer part adjacent the ultraviolet generator, are disposed at an angle to the parabola 115 approaching parallelism with the parabola 117, then the angle of reflection of the ultraviolet rays as indicated by the arrow 120 will be decreased and the reflected rays will more nearly approach parallelism with the axis of the parabola. In most cases, however, the target area will be too large to be covered by a parallel beam, and accordingly the reflecting portions 121 are preferably disposed at angles intermediate the parabolas 115 and 117 and such that ultraviolet rays are still reflected therefrom at an angle to the axis of the parabola but in a direction that more closely parallels said axis than the direction that the same rays would assume when reflected from a surface corresponding to the parabola 115. The angles of the portions 121 are suitably adjusted so that the reflected ultraviolet radiation is concentrated on the target area at the proper distance from the lamp, and is also distributed over the entire target area. It will be understood, of course, that the upper half of the reflector as seen in Fig. 16 is similarly constructed.

The resultant irregularity of the reflecting surface makes it difficult to draw or press the reflector to such perfection as to avoid strong and weak spots in the light pattern on the target. However, substantially uniform energy distribution can be obtained by the use of a large number of reflecting portions 121 of small size so as to produce a corresponding number of overlapping spots of light distributed over the target area. The overlapping and merging of these spots may be facilitated by making the reflecting portions 121 concave and preferably substantially spherical so that the reflected cones of light 122 are brought to a focus as indicated at the points 123 and then diverge as they approach the target. The portions 121 may thus be substantially circular in outline and present a "dimpled" appearance.

Radiation from the infrared generator is reflected in a substantially parallel beam by the inner portion of the reflector conforming to the parabola 115, as indicated by the broken lines 124. It is to be remembered, however, that in practice the generation of infrared rays is not confined to a point at the focus 116, but they are emitted from the whole ceramic element 54 and accordingly the reflected rays are not confined to the parallel beam 124. Also the portions 121 of the outer part of the reflecting surface are connected by intermediate portions 125 which are disposed at an angle to the parabola 115 as the result of the drawing or pressing operation. Infrared rays striking these portions 125 are reflected at an angle to the axis of the parabola as indicated by the broken lines 126. Because of these overlapping reflections, the infrared illumination of the target is not confined to a spot corresponding to the beam 124 but is spread out over the target area, and more uniform energy distribution is produced. These effects may be enhanced, if desired, by the provision of a number of small "dimples" in the inner portion of the parabolic reflecting surface as indicated at

127, and these dimples may be arranged in any desired manner in the interest of overall appearance of the reflector.

The reflector can be made by drawing or pressing a sheet of metal in a die, and the resulting product is preferably used alone as the cover 60 of the lamp. Fig. 17 shows the reflector in cross section in a plane at right angles to the axes of the generators. Apart from the dimples 121, the general or basic shape of the reflector is parabolic and conforms to the curve. In a typical case, the dimples 121 varied from $\frac{1}{4}$ " to $\frac{3}{8}$ " in diameter, and were curved on a radius of two inches. Under these conditions the depth of the depression at the center of the dimple was of the order of only 0.005 inch. The dimples can be arranged in rows extending in the direction of elongation of the reflector and more or less parallel to its outer edge or rim, and the dimples in adjacent rows can be staggered if desired for closer spacing of the rows and utilization of a maximum part of the reflecting surface. Such an arrangement is indicated diagrammatically in Fig. 18. Preferably the rows are continued around the end of the reflector.

Fig. 19 illustrates diagrammatically the results obtained with the above reflector on a target located about 18 inches from the lamp, only one side of the target being shown. The reflector 60, the infrared generator 54, and the ultraviolet generator 11 are constructed and located as described above. Ultraviolet rays emitted directly to the target are indicated by the lines 128. The cones 122 of ultraviolet radiation reflected from the portions 121 are focused at 123 and then diverge to form substantially circular spots of illumination 129 on the target. These spots overlap each other as shown to provide an approximately uniform pattern of illumination which is superimposed on the approximately uniform pattern of direct illumination 128. Thus ultraviolet radiation is concentrated on and distributed over the target area. Infrared radiation, either along with ultraviolet radiation or alone, reaches and is distributed over the target area by parallel beam reflection indicated by the broken lines 124 and by non-parallel rays within the broken lines 126.

It will be understood that the invention is not restricted to the embodiments illustrated in the drawings and described above but is capable of other embodiments, and also that various changes can be made in the form, details of construction, and arrangement of the parts without departure from its spirit. Reference therefore should be had to the appended claims for a definition of the limits of the invention.

What is claimed is:

1. A lamp of the type described comprising a base having a pivot mounting at one end, a cover unit movable into juxtaposition with said base and cooperating therewith to form a housing, said cover unit comprising a supporting plate and a dished elongated cover element pivoted at one end on said mounting, said plate having a section forming a partition across the end of said cover element adjacent said pivot mounting and said element beyond said partition comprising a reflector, a substantially tubular ultraviolet lamp and an elongated ballast resistance means extending in spaced substantially parallel relation with one another and with said reflector and each having one end mounted on said partition, a lamp

supply cord entering the compartment formed in the end of said cover unit behind said partition, and electrical connections between said cord, lamp and resistance means and enclosed in said compartment.

2. A lamp as defined in claim 1, said cover element being mounted on said plate and said plate being pivoted on said mounting.

3. A lamp of the type described comprising a base having a pivot mounting at one end, a cover unit movable about said pivot into juxtaposition with said base and cooperating therewith to form a housing, said cover unit comprising a dished elongated cover element pivoted at one end on said mounting and a supporting plate part of which forms a partition across the end of said dished cover element adjacent said pivot mounting, a substantially tubular ultraviolet lamp and a ballast resistance unit extending in spaced substantially parallel relation with one another and with said cover element, clamping means connecting the ends of said lamp and resistance unit together, means engaging said clamping means for mounting said lamp and resistance unit on said partition, reflector means on said cover element adjacent said lamp and resistance unit, a lamp supply cord entering the compartment formed in said cover unit behind said partition, and electrical connections between said cord, lamp and unit and enclosed in said compartment.

4. A lamp as defined in claim 3, including an insulating base plate interposed between the ends of said lamp and unit and the partition and having recesses to receive said ends, said electrical connections passing through said insulating base.

5. A lamp as defined in claim 4, including a terminal plate of insulating material on the opposite side of said partition from said base plate, said partition, base and terminal plates, lamp and resistance unit all being secured in assembled relation by said means engaging said clamping means, and said base and terminal plates and partition having aligned openings for the passage of said electrical connections.

6. A lamp as defined in claim 3, said resistance unit comprising a ceramic element having substantially the same length as said lamp, said ceramic element having longitudinally extending bores for a plurality of resistors constituting said resistance and additional longitudinally extending bores for connectors between the opposite ends of said lamp.
